SUPERVISORY CIRCUIT FOR TELEPHONE
SWITCHBOARDS

Richard P. Boyer, Jr., Newton, Mass.

Application February 4, 1939, Serial No. 254,693

9 Claims. (Cl. 179—51)

This invention relates to telephone circuits and has particular reference to switchboard circuits of the cordless type.

One of the objects of my invention is to provide a switchboard so constructed that the operator in charge will be advised when any of two or more connected parties has hung up and also which circuit in the switchboard needs attention following the discontinuance of use by any subscribers who may be connected to the switchboard.

A further object of my invention is to provide visual signalling means of a type that is very effective in calling the operator's attention to the circuits when changes need to be made.

Another object of my invention is to provide means for indicating to the operator when a party called by the operator has answered.

These and other objects of my invention will become apparent as the description proceeds with the aid of the accompanying drawing in which

Fig. 1 is a diagram of two connected lines in conjunction with my supervisory circuit as applied to one switchboard circuit.

Fig. 2 is a diagram of my supervisory circuit showing how it may be applied to one switchboard circuit and any number of lines.

Fig. 3 is a diagrammatic view of a typical type of cordless switchboard utilizing my circuit.

Referring to Fig. 1, the diagram shown in light lines represents a pair of lines extending to the switchboard and a connecting circuit in the switchboard. In practice, of course, there are a plurality of lines extending to the switchboard, and, in the switchboard, there will be a plurality of connecting circuits whereby the incoming lines may be connected to each other through different circuits as desired or depending on what circuits happen to be busy at the time the additional lines are to be connected.

In the drawing one subscriber is represented at 2 and the other subscriber at 4. The lines from these subscribers run to the switchboard on circuits 6 and 8. Intermediate thereof are ringing keys 10 and 12 by means of which alternating current may be impressed on circuits 6 and 8 to ring the subscribers' bells when desired.

One of the wires of circuit 6 passes through the ringing key 10 to wire 14, through key-operated switch 16 to wire 18, which in turn is connected to the retard coil 20, and thus to the positive terminal of battery 22.

The other wire of circuit 6 passes through the ringing key 10 to the relay 24, through key-operated switch 26 to wire 28, to retard coil 30, to the negative terminal of battery 22.

A separate circuit influenced by the relay 24 runs from ground 32 to switch 34, which is opened or closed by the operation of relay 24, to wire 36, which divides at 38, one path going to a lamp 40, which is known as a busy lamp, on through wire 42 to junction 44, and thence to the positive terminal of battery 22. From junction 38 the circuit also goes through resistance 46 to wire 48, to switch 50, and thence to junction 52 from which the circuit goes in one path to relay 54, on to the ground at 56. From junction 52 extends another wire 58 which is connected to all other key switching connections corresponding to switch 50 on the same connecting circuit, as will be more particularly explained hereinafter.

From junction 44 extends a wire 60, which may, if desired, pass through a relay 62 controlling an audible signal or buzzer, and thence through wire 64 to lamp 66, which lamp is known as a supervisory signal, and to which lamp is connected the switch 68 controlled by the operation of relay 54.

The switches 16, 26 and 50 are all under the control of a single key. For example, such a key may be key 70 in Fig. 3, which when thrown upwardly will close the three switches 16, 26 and 50 in circuit No. 1 of the switchboard. This, of course, assumes that circuit 6 coming from subscriber 2 is under the control of the switches in the column indicated by the arrow 72 in Fig. 3.

The procedure in signalling the operator is as follows. A subscriber removes his receiver from the hook, thereby closing a circuit to the line lamps 73 indicated in Fig. 3. The line lamp circuit, being conventional, is not shown. The operator, observing the lighted line lamp of the particular subscriber's line, thereupon moves a switchboard key associated with that line to connect the line with any connecting circuit on the board not in use. For example, key 70 may be moved forwardly to connect subscriber 2 with connecting circuit No. 1. The operator will also move her keys to corresponding positions so that she may converse with the subscriber to receive his instructions.

As soon as key 70 has been moved forward to connect subscriber 2 with connecting line 1, switches 16, 26 and 50 will be closed, causing current to flow through circuit 6. This, of course, causes operation of relay 24 to close switch 34, which permits the flow of current from battery 22, through busy lamp 40, to ground 32. Thus, busy lamp 40 is immediately illuminated as soon as the line of subscriber 2 is connected to a connecting circuit. Thereafter busy lamp 40 will remain on

until subscriber 2 either hangs up or key 70 is moved to off position.

Current will not flow through the circuit indicated by 46, 48, 50, 54 and 56 because zero potential exists at both 38 and 56. Thus, relay 54 is not in operation, and switch 68 will remain open so that no current will flow through supervisory signal 66. By the circuits described, busy lamp 48, shown in Figs. 1 and 2, and in row 12 of Fig. 3, 10 will be illuminated, but supervisory signal 66 for circuit No. 1 will not be lighted.

If subscriber 2 desires to be connected with subscriber 4 and so advises the operator, the operator in turn will move key 76, shown in Fig. 3 in column 74, (in which column all switches are connected with line 8 leading to subscriber 4,) to upward position, thereby connecting subscriber 2 with subscriber 4 through connecting circuit 1 of the switchboard.

20 The line lamps which light to signal the operator initially and which go out when the operator has responded to the subscriber are shown in Fig. 3 but constitute no part of this invention, as this is common construction.

25 Movement of key 76 to the upward position closes switches 78, 80 and 82 of subscriber 4's circuit 8, which circuit is similar to the circuit already described and has therein the relay 86 from which goes wire 83 to switch 80, and thence 30 through wire 90 to retard coil 30, to the negative terminal of battery 22. The other wire from line 8 of subscriber 4 passes through ringing key 12 to wire 92, through switch 78 to wire 94, to the retard coil 20, and thence to the positive terminal 35 of the battery 22.

After key 76 has been moved to upward position, but before subscriber 4's line has been closed by subscriber 4 answering the operator's signal, a circuit will be completed from the positive side 40 of the battery through wire 102, busy lamp 100, resistance 101, switch 82, wire 58, junction 52, relay 54, and ground 56, which in turn will cause switch 68 to be closed, thereby putting the supervisory signal in operation.

45 With current flowing through subscriber 4's circuit, which will occur after subscriber 4 has lifted his receiver and key 76 has been moved upwardly, relay 86 will operate to close switch 96 of the supervisory circuit, thereby creating a path from the ground at 98 to junction 99 through a 50 second busy lamp 100, to wire 102, to the positive terminal of battery 22. Lamp 100 will then be lighted in the same manner as lamp 40 after the necessary connections have been made by the operator and subscriber 4. Another path from junction 99 extends to resistance 101, similar to 55 resistance 46, through switch 82 to wire 58, hereinbefore referred to, and to junction 52.

60 Thus the two keys 76 and 78 will be moved in the same direction, the two busy lamps 40 and 100 will be lighted, but the supervisory signal 66 of the switchboard connecting circuit 1 will be out. This condition continues until either or 65 both of the subscribers 2 and 4 break one or both of the circuits by hanging up. Assume, for example, that the subscribers are about to hang up at the completion of the conversation.

When subscriber 2 hangs up, current will cease 70 flowing through relay 24, which will cause switch 34 to open, thereby breaking the circuit from the battery through busy lamp 40 to the ground, so that, were it not for the circuit through 46, 48, 50, 54 and 56, the lamp 40 would go out completely. However, with switch 34 now open, the current 75 from the positive terminal of battery 22,

which current formerly flowed to the ground at 32, now must pass through resistance 46, wire 48, switch 50, and relay 54 to ground 56. This current is sufficient to bring relay 54 into operation so that switch 68 is immediately closed. 5 There then becomes available a circuit from the positive terminal of battery 22 through junction 44, wires 60 and 64, supervisory signal lamp 66, switch 68, to ground 56, so that the supervisory signal 66 is illuminated. Resistance 46 so reduces 10 the current that busy lamp 40 is practically extinguished.

It will be seen that after switch 34 is opened by subscriber 2 hanging up, current may flow from the positive terminal of the battery to the grounds 56 and 98. There are two paths to ground 98, one through the busy lamp 100 and the other through resistances 46 and 101. There are two paths to ground 56 (assuming switch 68 not closed as yet) one which includes resistance 46 and relay 54, and the other resistance 101 and relay 54.

Because the combined resistances of 46 and 101 are greater than the combined resistances of 46 and 54, sufficient current will flow through 25 relay 54 to operate switch 68, with the result that supervisory lamp 66 will be lighted. Conversely, if subscriber 4 hangs up first, resistances 46 and 101 being greater than the combined resistances of 101 and 54, the relay 54 will function to cause 30 the current of the supervisory circuit to operate relay 54 to close switch 68 and light supervisory lamp 66.

The operator, on observing the board, is immediately informed by virtue of lamp 66 being 35 lighted that one or the other or both of the subscribers have broken their circuits and that attention is needed. Since it is supervisory signal 66 that is now in operation, it is indicated that the lines that need attention are those lines connected through the switchboard by connecting circuit No. 1, and by reference to the keys of circuit No. 1 that have been moved to upward position it may be determined readily which subscriber's circuit has been discontinued and the 40 appropriate key may be drawn back to off position. If key 76 is operated, thereby opening switches 16, 26 and 50, relay 54 will be rendered 45 inoperative, switch 68 opened, and supervisory signal 66 extinguished.

If subscriber 4 had hung up, thereby breaking 50 circuit 8, the same result would have been obtained; namely that busy lamp 100 would be greatly dimmed, while supervisory signal 66 would be illuminated until extinguished by movement of key 76 to off position.

I should point out here that for each line running from a subscriber to the switchboard there is the usual line signal, shown in Fig. 3, and one busy signal, but there is only one supervisory signal for each connecting circuit that is present in the switchboard, regardless of the number of lines that may be connected through this connecting circuit. Thus, no matter how many lines may be connected through any selected switchboard connecting circuit, the supervisory signal will always be operative to indicate the condition of lines to the board connected through the particular switchboard circuit in use when any of the subscribers' lines have been broken.

70 Similarly, there is a supervisory signal 104, as shown in Fig. 3, which indicates the condition of lines connected through connecting circuit No. 2, and there is another supervisory signal 106 indicating the condition of lines connected through 75

connecting circuit No. 3. There may be as many connecting circuits as desired in a switchboard of this type, but for each connecting circuit there will be a supervisory signal.

5 Likewise, the busy signal lamps 108 and 110 relate to other subscriber's lines that are under control of the switches in columns 112 and 114 respectively. Obviously there may be as many subscribers' lines coming to the switchboard as 10 desired, although the greater the number, the more complicated the wiring will necessarily become in order that the various connections may be made through the key switches.

15 In further explanation of the above I have provided in Fig. 2 a diagram of a supervisory circuit for any connecting circuit on the switchboard. This circuit is the same as that of Fig. 1, but arranged differently to show certain aspects 20 more clearly. In this diagram the subscribers' lines and connections through the connecting circuit in question are omitted for clarity in showing the operation of the supervisory circuit.

25 As pointed out above, for each connecting circuit there is one supervisory circuit, and this latter circuit will function in connection with any 30 or all lines that may be connected to the connecting circuit under control of this supervisory circuit.

35 In the diagram of Fig. 2 it is contemplated that there are three subscriber's lines running to the switchboard, and each of the switches 34, 96 and 116 is under the control of a relay operable when the subscriber's line is closed, such relays being indicated at 24, 86 and 118. All of the relay-controlled switches are grounded either by a common ground or individually, as at 32, 98 and 120. From each of the switches extends a wire to busy lamps 40, 100 and 108, from which extend connections to the positive terminal of battery 22.

40 From each of the switches 34, 96 and 116 also extends a path including a resistance, as 46, 101 and 122, and from the resistance a wire extends to the key-controlled switches 50, 82 and 124. To these switches is connected a common wire 58 which extends to relay 54, to the ground at 56.

45 Connected with the lead from the positive terminal of battery 22 is wire 64, which connects with supervisory signal 66, from which runs a connection to switch 68, which is operable under the influence of relay 54.

50 From this diagram it is believed clear that there may be as many busy lamps, as 40, 100 and 108, as there may be subscribers' lines; and each busy lamp will be under the influence of a relay, as 24, 86 and 118, in that subscriber's line.

55 Considering the operation of subscriber 2's line, which includes relay 24, it may be seen that 60 when that line is closed, switch 34 will be closed, completing a path from the positive terminal of the battery, through busy lamp 40, to ground at 32, which causes the busy lamp to light. Similarly, when switches 96 and 116 are closed by 65 virtue of other subscribers' lines being in operation, busy lamps 100 and 108 will also be illuminated. With switches 34, 96 and 116 closed, the busy lamps are unaffected by the position of the key controlled switches 50, 82 and 124, as no 70 current will flow through these portions of the circuit because both ends of the portions in question are at ground potential at 32 and 56. Thus with switches 34, 96 and 116 closed, no current 75 will flow through relay 54, with the result that

switch 68 will remain open and the supervisory lamp 66 will be out.

As soon, however, as any subscriber hangs up, the relay in that subscriber's line will become inoperative, opening the appropriate switch on 5 the supervisory circuit. Thus, for example, if relay 24 becomes inoperative, switch 34 will open so that current from the battery flowing through busy lamp 40 must now pass through resistance 46 and thence through switch 50, to relay 54, to ground 56. Resistance 46 is so great that for practical purposes the current falls to a point where lamp 40 goes out, or at least becomes very dim. But the current that does flow is sufficient to operate relay 54 to close switch 68.

15 As a result of this, the instant a subscriber hangs up, the busy signal on his line goes out and the supervisory signal 66 comes on. The operator will then move the appropriate key of the circuit to which that subscriber has been 20 connected to off position, and in this case switch 50 would be opened by the movement of key 70. As soon as switch 50 is opened, the current to 25 relay 54 is cut off so that the switch 68 opens and the supervisory signal 66 goes out.

30 The same procedure takes place when any other subscriber hangs up, so that the operator is immediately advised of the condition of all lines on any connecting circuit to which they are connected.

35 From the foregoing description it will be seen that by my circuit I am enabled to provide supervision for a switchboard which will enable the operator to know immediately when any subscriber's line connected to any connecting circuit has been broken by the subscriber hanging up, and, in addition, which of the lines has been broken. It is unnecessary to wait until all lines have been broken before receiving the supervisory signal. The supervisory signal becomes evident 40 immediately upon the breaking of the circuit of any subscriber connected to a connecting circuit.

45 I claim:

1. A telephone switchboard supervisory circuit comprising a plurality of parallel circuits, each including a lamp and a switch operable by a relay in series with a line, each of said parallel circuits having a common connection, said common connection including for each circuit a resistance and a manually operated switch, said common connection being connected to the ground, said ground connection including a relay, a connection extending from a point between said ground connection relay and the ground to said parallel circuits, said last-mentioned connection having therein a switch operable by said ground connection relay and a lamp.

50 2. A telephone switchboard supervisory circuit comprising a plurality of parallel circuits, all of 55 said circuits including a lamp and a relay operated switch, the said switches in all of the circuits except one being operable by relays under the control of lines to the switchboard, the switch of said other parallel circuit being under the control of a relay in a circuit connecting each of the other parallel circuits and the ground.

3. A telephone switchboard supervisory circuit as set forth in claim 2 in which the connection between each of the other parallel circuits having line-operated relay controlled switches and the ground includes a relay, a switch, and a resistance.

4. A telephone circuit comprising a plurality of subscribers' lines, a switchboard connecting 75

- circuit, and a supervisory circuit, a relay in and operable by each subscriber's line to actuate a corresponding switch in the supervisory circuit, a plurality of key switches for simultaneously 5 making connections in the subscribers' lines and in the supervisory circuits, busy lamps in said supervisory circuit for said switchboard connecting circuit, means for actuating the busy lamp of any subscriber's line when said line is in use 10 and the key switch of the connecting circuit relating to said line is closed, a supervisory lamp and means for actuating said supervisory lamp whenever thereafter any subscriber's line is broken.
- 15 5. A telephone switchboard supervisory circuit comprising a plurality of parallel circuits, each of said parallel circuits comprising a battery, a busy lamp and a relay operated switch, each of said parallel circuits having connected thereto 20 and extending to the other terminal of the battery a circuit comprising a resistance, a key operated switch and a relay, and another circuit parallel to said last-mentioned circuit including a lamp and a switch operable by said last-men- 25 tioned relay.
6. A telephone switchboard supervisory circuit comprising a plurality of parallel circuits, each of said parallel circuits comprising a battery, a busy lamp and a relay-operated switch, each of 30 said parallel circuits having connected thereto and extending to the other terminal of the battery a circuit comprising a resistance, a key-operated switch and a relay, and another circuit including a power supply, a lamp and a switch 35 operable by said last-mentioned relay.
7. A telephone switchboard supervisory circuit comprising a plurality of parallel circuits, each including a lamp and a switch operable by a re-
- lay in series with a line, each of said parallel circuits having a common connection, said common connection including for each circuit a resistance and a manually operated switch, said common connection including a relay, and a circuit 5 including a power supply, a lamp, and a switch operable by said relay in said ground connection.
8. A telephone circuit comprising a plurality of subscribers' lines, a switchboard connecting circuit and a supervisory circuit, a relay in and 10 operable by each subscriber's line to actuate a corresponding switch in the supervisory circuit, a plurality of key switches for simultaneously making connections in the subscribers' lines and in the supervisory circuit, busy lamps in said 15 supervisory circuit for said switchboard connecting circuit, means for actuating the busy lamp of any subscriber's line when said line is in use or when the key switch of the connecting circuit 20 relating to said line is closed, a supervisory lamp, 20 and means for causing the operation of said supervisory lamp whenever no current is flowing in a subscriber's line which is connected to said connecting circuit.
9. A telephone switchboard supervisory circuit 25 comprising a plurality of parallel circuits, each of said circuits including a lamp and a relay operated switch, said switches in all of the circuits being operable by relays under the control of lines to the switchboard, a circuit connecting 30 each of said parallel circuits and the ground and comprising a relay, a switch, and a resistance, a supervisory lamp in a circuit having a power supply and a switch, said last-named switch being under the control of the relay in the circuit 35 connecting the parallel circuits and the ground.

RICHARD P. BOYER, JR.
